UNITED STATES PATENT OFFICE.

ADOLPH LANGSNER, OF CHICAGO, ILLINOIS, ASSIGNOR TO EUGENE DIETZGEN COMPANY, OF CHICAGO, ILLINOIS, A CORPORATION OF DELAWARE.

STOPPER FOR INDIA-INK BOTTLES AND THE LIKE.

Application filed April 22, 1928. Serial No. 272,253.

My invention relates to stoppers for india ink bottles and the like which are adapted to carry a quill or equivalent tool.

One of the objects of my invention is to provide a stopper for an india ink bottle which stopper is formed of sheet metal in part so as to be capable of screwing upon the threaded neck of a bottle and in addition is provided with a simple means for carrying a quill or other tool which depends into the bottle when the stopper is in position.

The detailed objects of my invention reside in providing a simple mounting carried by the sheet metal portion of the stopper for holding the quill whereby economical construction and simplicity in operation and assembly is assured.

These and other objects of my invention will be apparent from a perusal of the following specification when taken in connection with the accompanying drawings, wherein:

Figure 1 is a perspective view of one form of my closure as applied to the india ink bottle;

Figure 2 is a modified form of my invention;

Figure 3 is a view of the construction showing the central holding tube smashed down to secure it in position in the sheet metal closure and wherein the sheet metal closure is provided with a steeple of moldable material;

Figure 4 is still another modification;

Figure 5 is yet another modification showing the rivet used for securing the quill to the sheet metal cap;

Figures 6 and 7 are views showing the rivets smashed into position and with or without the moldable material forming the steeple; and

Figure 8 is an under side view of the sheet metal portion of the cap.

Referring now to the drawings in detail, I prefer to illustrate my invention in connection with the usual type of ink bottle for holding india ink such as used by draftsmen and the like. This bottle 2 is formed on its neck 4 with the usual glass screw threads 6 which may be of any type, either of continuous threads or mutilated threads or spaced apart lugs. It will be understood that the shape of the bottle and the arrangement of the threads, except in so far as to cooperate with my novel type of stopper, constitute no part of my invention.

In the form illustrated in Figure 2, my invention comprises a sheet metal screw cap formed with the usual depending peripheral flange 8 which is formed at appropriately spaced portions with inwardly projecting ears or lugs 10 adapted to engage under the threads 6 on the neck of the bottle as is well known in the art. The upper or top surface 12 of this screw cap is provided with an opening through its central axis. The stopper also includes a quill holder which in my present invention includes several forms. In the form shown in Figure 2, this quill holder comprises the metal cup-like cylinder 14 preferably provided with a rounded dome 16. This cylinder is slightly indented as at 18, to fit snugly in the central opening of the top 12 of the screw cap, whereby the tube 14 and the screw cap are held in assembled relation. In addition, the screw cap receives therein a washer 20 of cork or other compressible material which is held in place by the shoulder on the cylinder 14 formed immediately below the annular crimp 18. If desired, the top of the screw cap 12 may be provided with an annular depression 22 for ornamental purposes and also for giving the cork a slight spacing disposition with respect to the top of the screw cap whereby to increase the resiliency somewhat of this washer 20. As shown in Figure 3 of the drawing, the metal cap with the cylinder 14 assembled thereto is placed in a die and the curved head 16 is flattened or crushed down into the position illustrated in Figures 3 and 4, which serves permanently to assemble these elements together and also to hold the washer in place within the screw cap. The quill is frictionally mounted within the cylindrical tube 14 in which it fits snugly. This is shown in Figure 3 of the drawings wherein the upper end 24 of the quill is shown as abutting the shoulder 26 formed by the annular crimp 18. The constructions shown in Figures 2 and 3 are identical except that in the matter the sheet metal screw cap is provided with a steeple 28 of hard rubber or other moldable material which depends down to the bottom of the flange 8 of the screw cap and wholly encloses and hides it. The exterior basal portions of the steeple are provided with knurled portions 30 for facilitating gripping.

and the faces of both the steeple and the lower portions are provided with angularly shaped sides 32 and 34 respectively to prevent the steeple from rolling about.

5 In Figure 4 of the drawings, an identical construction to that shown in Figure 3, except that no steeple is used, is provided, the differences being that the cylindrical tube 30 thereof receives the quill 32 on the outside, the upper edge of the quill abutting the cork washer 34. Otherwise the constructions are substantially identical. It will be obvious that the construction shown in Figure 4 may also be provided with a steeple if desired.

10 15 In Figures 5, 6, and 7, I have shown a modified form of attachment for mounting the quill on the sheet metal closure. In this instance, the sheet metal cap 36 is provided with a central opening in which and through 20 which passes a rivet of metal having the head 38, an intermediate washer 40, and a shank 42, which may or may not be hollow. The head 38 of the rivet passes through the opening in the top 44 of the sheet metal screw cap, where 25 it may be peened into permanent assembly thereon as shown in Figures 6 and 7. The washer 46 of a cork or other compressible material is mounted within the sheet metal cap 36 between the washer 40 and the inner top 30 44 of the cap. The quill 48 is adapted to be slipped over the lower portion 42 of the rivet so that the upper end of the quill backs against the washer 40 of the rivet, thereby positioning the quill with respect to the cap. In Figure 6, the sheet metal cap shown in Figure 5 is provided with a steeple 50 of a construction like that shown in Figure 1.

35 In Figure 7 of the drawings, a sheet metal cap similar to that shown in Figures 5 and 6 is employed except that the lower portion 52 of the rivet is hollow to receive directly therein the quill 54 which fits in place by means of frictional contact. The top end of the quill fits against the washer 56 of the rivet. In 40 both of these instances the cork washer is held in position. It is also obvious that in any of these constructions either the steeple or unsteepled arrangement may be used.

45 By reason of the foregoing, it will be appreciated that I have provided a very simple construction and assembly for mounting a quill or other tool on a sheet metal cap or closure for an india ink bottle or the like. In the present instance, the sheet metal screw cap is highly desirable since it is wholly positioned on the neck of the bottle in a predetermined manner whereby the bottom of the quill is always positioned exactly at the correct distance from the bottom of the bottle 50 whereas in former cork constructions, due to an accretion of ink on the cork, the latter would tend to stick in the bottle and would rest higher or lower in the neck, depending upon the amount of accretion on the cork.

60 65 Furthermore, the present construction pro-

vides a facial manner of permitting the opening and closing of the cork bottle while at the same time permits a very simple mounting for the quill or other tool carrying member. In the arrangement shown in Figures 2, 3, and 4, 70 the utilization of the cylindrical tube of sheet metal for receiving the hollow quill either within or without its surface, not only provides an expedient means for rapidly mounting the quill and providing a rivet seat or 75 backing for the top thereof whereby to provide accurate spacing for the bottom of the quill from the bottom of the bottle, but it also provides a very neat and simple means for permitting the quill mounting to be quickly 80 assembled to the sheet metal cap since a peening operation accomplishes this result.

85 So also in the rivet construction shown in Figures 5, 6, and 7, the head 38 of the washer when peened down accomplishes this same assembly and the circular washer portion 40 provides a firm mounting for the cork insert and for providing a backing member for the quill. In addition the lower portion of the rivet provides a neat and effective seat for the 90 quill which may be mounted thereon either with or without this portion.

95 Having thus described my invention, what I claim as new and desire to protect by Letters Patent is:

100 1. A stopper construction for india ink bottles comprising a sheet metal screw cap provided with a peripheral flange and a top, said flange having locking means for engaging the locking projections on the neck of a bottle, and an opening through the top of said cap, a cup-like cylinder inserted through the opening in said top and having a closed head, said head being peened over the edges of said opening in the top, a cork washer mounted 105 within the under surface of the sheet metal cap on said cylinder, and a quill carried by said cylinder in position to depend within the neck of the bottle when said cap is screwed thereupon.

110 2. A stopper construction for india ink bottles comprising a sheet metal screw cap provided with a peripheral flange and a top, said flange having locking means for engaging the locking projections on the neck of a bottle, and an opening through the top of said cap, a cup-like cylinder inserted through the opening in said top and having a closed head, said head being peened over the edges of said opening in the top, a cork washer mounted 115 within the under surface of the sheet metal cap on said cylinder, and a quill carried by said cylinder into position to depend within the neck of the bottle when said cap is screwed thereupon, and a steeple of moldable material 120 covering the external surface of said screw cap and overlying the peened portion of said cylinder.

125 3. In a device of the class described, the combination of a screw cap having locking 130

means for engaging cooperative locking means on the neck of a bottle, a metal cylinder passing through a central hole in the top of said screw cap, said cylinder having a portion projecting through said opening and peened thereover and a quill carried by that portion of the cylinder lying within the interior of the screw cap.

4. In a device of the class described, the combination of a screw cap having locking means for engaging cooperative locking means on the neck of a bottle, a metal cylinder passing through a central hole in the top of said screw cap, said cylinder having a portion projecting through said opening and peened thereover and a quill carried by that portion of the cylinder lying within the interior of the screw cap, and a washer of compressible material surrounding said cylinder and assembled on the under face of the top of the screw cap.

5. In a device of the class described, the combination of a screw cap of sheet metal and having locking means for engaging cooperative locking means on the neck of a bottle, said screw cap having a central opening in the top, a metal cylinder having a closed top projecting through said opening and provided with an annular crimp portion in which the edges of said opening fit, said projecting portion being peened or flattened to overlie the edges of said opening at the top of the cap, and a quill mounted within said cylinder and having the top edges of said quill resting against said annular crimp.

6. In a device of the class described, the combination of a screw cap of sheet metal and having locking means for engaging cooperative locking means on the neck of a bottle, said screw cap having a central opening in the top, a metal cylinder having a closed top projecting through said opening and provided with an annular crimp portion in which the edges of said opening fit, said projecting portion being peened or flattened to overlie the edges of said opening at the top of the cap, and a quill mounted within said cylinder and having the top edges of said quill resting against said annular crimp, and a washer of compressible material fitting on said cylinder and covering the inner under side of said screw cap.

7. A screw cap covering for india ink bottles having a separate metal sleeve passing through a central opening in the top of the cap with the upper portion of said sleeve peened in position, a washer of compressible material fitting around that portion of the

cylinder lying within the cap, and a quill mounted on said cylinder with the top of the quill abutting said washer.

8. In a device of the class described, the combination of a screw cap of sheet metal having locking means for engaging cooperative locking means on the neck of a bottle, said screw cap having a central opening in its top, a metal rivet having a head portion projecting through said opening, an integral washer overlying said opening and a depending stud, said head being riveted in position whereby to permanently unite said rivet to the top of said cap, and a quill mounted on said depending portion of the rivet.

9. In a device of the class described, the combination of a screw cap of sheet metal having locking means for engaging cooperative locking means on the neck of a bottle, said screw cap having a central opening in its top, a metal rivet having a head portion projecting through said opening, an integral washer overlying said opening and a depending stud, said head being riveted in position whereby to permanently unite said rivet to the top of said cap, and a quill mounted on said depending portion of the rivet, and a washer of compressible material disposed between the washer of the rivet and the inner under side of the top of the sheet metal cap.

10. A sheet metal screw cap for india ink bottles and the like having a rivet peened through a central opening in the top of said cap, said rivet having an integral washer of a larger diameter than the hole through said cap and underlying said hole, a washer of compressible material held by said first mentioned washer against the under side of the top of the cap, and a quill mounted on a depending portion of said rivet with the top of the quill backing against the washer of the rivet.

11. A sheet metal screw cap for india ink bottles wherein the top of the screw cap is provided with a hole, a metal rivet passing through said hole with the projecting portion thereof peened over the opening of said steeple, said rivet having a washer lying within the screw cap and a washer of compressible material held against the under side of the top of said screw cap by said washer, said rivet having a hollow depending shank, and a quill mounted within said hollow shank.

In witness whereof, I have hereunto subscribed my name.

ADOLPH LANGSNER.
